UNITED STATES PATENT OFFICE.

DAVID M. HOLBROOK, OF PORTLAND, OREGON.

INCUBATOR HUMIDIFIER.

Application filed August 24, 1922. Serial No. 584,150.

To all whom it may concern:

Be it known that I, DAVID M. HOLBROOK, a citizen of the United States, residing at Portland, in the county of Multnomah and 5 State of Oregon, have invented certain new and useful Improvements in Incubator Humidifiers; and I do declare the following to be a full, clear, and exact description of the invention, such as will enable others 10 skilled in the art to which it appertains to make and use the same.

My invention relates to improvements in humidifying devices for incubators and is directed to certain subject matter originally 15 shown by my U. S. application which terminated in Patent 1,417,522 of May 30th, 1922, but was eliminated on account of a requirement of division.

The present invention has for its principal 20 object to provide a humidifier including a water tank in communication with the incubator and provided with a water circulating pipe heated by the usual incubator lamp, whereby the water of the tank is caused to give up vapor for moistening the 25 air within the incubator, the arrangement being such that while the water-circulating pipe passes across the chimney of the lamp, it will not interfere with removal of the 30 lamp and chimney when the former is to be filled or its wick trimmed.

A further object is to provide an arrangement which is such as to permit the lamp 35 to be adjusted in such a manner that more or less of its thin flat flame, may play upon the water circulating pipe, whereby to heat the water in the humidifying tank to a greater or less extent, as may be necessary.

With the foregoing and minor objects in 40 view, the invention resides in the novel subject matter hereinafter described and claimed, the description being supplemented by the accompanying drawings.

Figure 1 is a front elevation of an incubator equipped with my invention, parts being shown in vertical section.

Figure 2 is a vertical transverse section taken on line 2—2 of Fig. 1 with parts in elevation.

Figure 3 is a horizontal section as indicated by line 3—3 of Fig. 1.

Figure 4 is a detached perspective view of the humidifying tank and its water circulating pipe.

55 In the drawings above briefly described, the numeral 1 designates an incubator hav-

ing a casing 2 secured on one end, said casing containing a vertical sleeve 3 in the upper portion of which a boiler 4 is located, said boiler having water circulating pipe 5 leading into the incubator. The numeral 6 merely designates a reservoir on top of the casing 2 for keeping the boiler and the pipes 5 full of water, being in communication with one of said pipes by means of a pipe 7. 60 Suspended by links or the like 8 from the bottom of the casing 2, is an appropriate lamp 9 whose chimney 10 extends into the lower end of the sleeve 3, said chimney being provided with vertical slots 11 which 65 open through its upper end for a purpose to appear.

Within the casing 2 and preferably interposed between the sleeve 3 and the incubator 1, is a humidifying tank 12 open at its 70 upper end whereby it may communicate with the interior of the incubator 1, through the medium of an appropriate passage 13, shown in Fig. 2. At spaced points, a pair of angular pipes 14 depend from the bottom of the tank 12 and one of these pipes 80 preferably extends into the tank to a greater extent than the other, the two pipes being connected by a horizontal pipe 15 which passes across the lower end of the sleeve 3 85 and is received in the slots 11 of the lamp chimney 10. It will thus be seen that the flame of the lamp, indicated in Figs. 1 and 2 by the numeral 16, will heat the pipe 15 and cause circulation of water through this 90 pipe and the humidifying tank 12, thereby causing the water in this tank to give off vapor which may pass to the incubator through the passage 13. Attention may here be directed to the fact that by setting 95 the burner of the lamp 9 so that its flat flame 16 plays longitudinally upon the pipe 15, maximum heating of the latter may be effected, but by turning said burner so that the flame plays obliquely or at right angles 100 to the pipe 15, the latter will be heated to a lesser degree, due to the restricted part of the flame then acting upon the pipe. Thus, the extent to which the water in the tank is heated, may be controlled in the required 105 manner.

Water may either be supplied to the tank 12 by means of a water supply pipe 17 connected with the pipe 15 or by means of a short vertical pipe 18 which rises through 110 the top of the casing 2, and the rate of water circulation may be controlled by an appro-

priate valve 19 positioned at any suitable point. The pipe 18 preferably extends to quite an extent into the tank 12 so that when this tank is substantially full of water, 5 no steam will be discharged through said pipe 18, but when the water level lowers to an undesirable extent, the attendant of the incubator is warned by steam escaping through the pipe 18, so that the water supply 10 may be replenished. When using the pipe 18 as an indicator as above described, the cap on the upper end thereof should be left off or fitted loosely so as to permit the escape of steam through the pipe.

15 From the foregoing taken in connection with the accompanying drawings, it will be seen that although my invention is simple and inexpensive, it will be highly efficient and desirable for the purpose intended. 20 Since excellent results may be obtained from the details disclosed, they may well be followed, but within the scope of the invention as claimed, numerous minor changes may of course be made.

25 I claim:

1. A humidifying device comprising an open ended tank for communication with a chamber, a water circulating pipe connected with said tank and having a horizontal por-

tion, a vertically disposed sleeve across the 30 lower end of which said horizontal pipe extends, and a lamp supported below said sleeve and having a chimney received in the latter, both sides of said chimney being formed with vertical slots opening through 35 its upper end and receiving said horizontal pipe portion.

2. The combination with an incubator having an external casing, an upstanding boiler containing sleeve rising through the 40 latter, and a lamp supported below said sleeve and having a chimney positioned removably within the lower end of said sleeve; of a humidifying tank open at its upper end and positioned between said sleeve and the 45 incubator, angular pipes depending from said humidifying tank, and a horizontal pipe connecting said angular pipes and extending across the lower end of said sleeve to provide water circulating means, the 50 chimney of said lamp being formed with opposed slots opening through its upper end, said slots receiving said horizontal pipe.

In testimony whereof I have hereunto af- 55 fixed my signature.

DAVID M. HOLBROOK.
